(57) **CLAIM**

The ornamental design for a bread box, as shown and described.

DESCRIPTION

FIG. 1 is a perspective view of a bread box showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the bread box where the bread box is in an opened state.

The broken lines in the drawings depict portions of the bread box that form no part of the claimed design.
